THREAD SPOOL AND THE METHOD OF
CONSTRUCTING THE SAME

Davis Marinsky and Louis H. Morin, Bronx, N. Y.

Application June 1, 1939, Serial No. 276,784

12 Claims. (Cl. 112—251)

This invention relates to thread spools, commonly referred to as a bobbin for use in connection with the shuttles of sewing machines, or to any other type and kind of spools for supporting threads, lines, cords, wires and the like. More particularly, the invention relates to the method of constructing end flanges of spooled strands of the type and kind under consideration, wherein the strands are cross-wound on the spools, and in using wax or paraffin flanges having weakened wall structures to provide for automatic removal of the flanges in the process of unwinding or removing the strand from the spool. The novel features of the invention will be best understood from the following description when taken together with the accompanying drawing, in which certain embodiments of the invention are disclosed and in which the separate parts are designated by suitable reference characters in each of the views, and in which:

Fig. 1 is a sectional view through a spool made according to the invention.

Fig. 2 is a face view of the spool shown in Fig. 1.

Fig. 3 is a perspective view of the spool illustrating the arrangement of strand windings thereon.

Fig. 4 is a diagrammatic sectional view illustrating steps in the method of producing spools according to the invention.

Fig. 5 is a view similar to Fig. 4 showing parts in a different position.

Fig. 6 is a view similar to Fig. 2 showing another form of construction, and

Fig. 7 is a view similar to Fig. 2 showing another form of construction.

The present device and method constitutes a continuation in part of the device and method disclosed in our prior application, Ser. No. 263,136, filed March 21, 1939.

In Figs. 1 to 3 inclusive is shown, for the purpose of illustrating one use or adaptation of the invention, a spool 8 for supporting thread and commonly referred to as a bobbin, and is adapted for use in connection with the shuttles of sewing machines. At 9 is shown the core or mandrel upon which the thread 10 is wound in the usual crossed relationship as is clearly illustrated in Fig. 3 of the drawing. On the side surfaces of the spool and arranged directly upon and secured to the thread 10 or the separate windings thereof where they extend to the side edges of the spool, are flanges 11, 11a both of which are of the same general construction aside from any question of color, and are composed of wax, par-

affin or other similar materials or compositions suitable for the intended purpose.

The surfaces of the flanges 11, 11a are provided with circumferential grooves 12 which extend throughout the entire area of the flanges and are of sufficient depth to weaken the wall structure of the flanges so that as the thread is unwound from the spool, pieces or particles of the flanges will be automatically removed by the thread so that when all of the thread on the spool has been removed, the flanges will also have been removed. The cross wound spools in question having what is generally referred to as universal windings, has each turn of the thread in contact with at least one of the side flanges, which will bring about the results above stated.

As is taught in our prior application, it will be understood that the compositioned flanges adhere to the threads sufficiently to hold the thread from unravelling or from accidental unwinding in the stopping of a sewing machine. However, the threads will be forcibly removable from the flanges and the flange parts will break up and be discarded as the weakened grooved portions are reached.

While from actual experience the structure as disclosed in Figs. 1 to 3 inclusive operate satisfactorily to accomplish the desired result, in some instances we may also provide a series of radial grooves or impressions as indicated at 13 and 14 in Fig. 6 of the drawing in conjunction with circumferential grooves 12a similar to the grooves 12. In this connection it will be understood that any other desired arrangement of the grooves or weakened areas might be provided, it being understood in this connection that the illustration in Fig. 1 of the drawing is somewhat exaggerated for clearness in illustration. The film-like flange coating of the composition material is relatively thin, and as a matter of fact the degrees of thickness may be varied by the stripping or scraping tool which is employed and later described.

In Fig. 7 of the drawing is shown a slight modification of the structure shown in Figs. 1 to 3 wherein a spiral groove 12b is provided rather than the series of circumferential grooves, and it will be apparent that the supplemental radial grooves as at 13, 14 in Fig. 6 are also applicable to a structure such as shown in Fig. 7.

In Figs. 4 and 5 of the drawing we have diagrammatically illustrated the method of applying and processing the compositioned flanges 11, 11a. In these figures, 15 represents a tank or crucible in which the wax, paraffin or other com-

position 16 is arranged and heated through any desired heating medium to a predetermined temperature, at least sufficient to provide a fluid consistency of the material in the tank 15. At 5 17 is shown a pan supported on an arm 18 pivoted as seen at 19 so that the pan is normally submerged in the material 16, as indicated in Fig. 5 of the drawing, and is raised into a definite or fixed position as shown in Fig. 4 for the purpose 10 of maintaining at all times a fixed level of the composition 16 as indicated at 16a in Fig. 4 so that the lower surface of the spool 8 supported upon a spindle 20 can be moved into definite and predetermined relationship with respect to 15 the level 16a in the movement of the spindle 20 toward and from the pan 17, so as to maintain at all times a controlled, regulated and balanced application of the compound to the lower surface of the spool. In other words, it will be apparent 20 that in providing a definite movement of the spindle in the dipping operation in conjunction with the provision of the constant fixed level of the composition 16a, each spool as well as each side surface of the spool, will be submerged the 25 same degree so as to provide a balanced application of the coating material.

It is also desirable in the movement of the spindle 20 toward and from the level 16a, to raise the spindle slightly after the first contact with 30 the composition, and then return it for a second submersion or contact before moving the spindle and spool away from the pan 17 for further processing. When raised into a position as shown in Fig. 5 of the drawing, the same is held in this 35 position for a short period of time to allow the composition to congeal or solidify to some degree. The spindle is then rotated fast so that centrifugal action will spread the composition more or less evenly upon the surface of the spool, 40 after which a scraping and grooving tool 21 is moved into position beneath the lower surface of the coated spool and in spaced relation to the wax coating 16b arranged thereon. The tool is moved in the direction of the coated surface of 45 the spool while the same is rotated so as to form the grooves 12 therein by the teeth 22 provided on the upper surface of the tool. This tool, in addition to forming the grooves 12, also removes 50 surplus material 16b so as to produce on the finished spool the compositioned flanges 11, 11a of predetermined thickness. The removed surplus and the material removed in forming the grooves 12 will drop back into the tank 15 and be remelted. It will be understood that the tool 21 55 is in the form of an arm extending from a sleeve 23 oscillating on a shaft 24, the tool being actuated through the medium of a crank arm 25 to which an operating lever 26 is connected, or any other means may be provided for this purpose. 60 This construction is to move the tool into and out of the path of movement of the spindle or the workpiece supported thereon, as will be apparent. It will also be understood that the tool 21 may 65 be moved into position beneath the spool just prior to the starting of the spool rotation or while the spool is being rotated.

It will be understood that after one side surface of the spool has been processed, the spool is 70 inverted on the spindle to cut or process the other surface thereof, and the above described operation will be repeated. The particular means for applying and removing the workpiece or spool with respect to the spindle is not disclosed as it 75 forms no specific part of the present method, and

this operation may of course be performed by hand or automatically, as desired.

It will be understood that in producing the structure shown in Fig. 7 of the drawing, instead of using a series of teeth or projections 22 on the tool, a single tooth will be employed and automatically fed inwardly and radially with respect to the spindle in the rotation of the spindle, suitable means being provided for operating the tool in this manner in conjunction with the swinging movement provided therefor to move the tool toward and from the workpiece.

With the construction shown in Fig. 6, the radial grooves or impressions may be formed by placing the flanged spool between dies which will 15 form the said radial grooves therein, and both surfaces may be grooved in this manner in one operation or in two independent operations, one on each surface of the spool.

It will be understood that our present invention is applicable to spools of different types and kinds of materials and of different structural arrangement, in accordance with the teachings in our prior application. It will also be apparent that in further processing the spool in accordance with the teachings in Fig. 6 of the drawing, instead of applying simply radial grooves or impressions, trade names or other markings might be formed in the surfaces of the flanges independent of or in conjunction with other markings 30 which would provide substantially the same characteristics of the structure as shown in Fig. 6.

Having fully described our invention, what we claim as new and desire to secure by Letters Patent is:

1. A spool of strand-like material comprising a core with the strand-like material wound in crossed relationship thereon, the sides of said spool comprising discs of relatively soft plastic material extending from the core to the outermost windings of the strand on said spool, and the outer surfaces of said discs having grooves extending over substantially the entire area thereof to weaken the structure of the discs causing said discs to break up into particles removable from the spool in the process of unwinding the strand therefrom.

2. A spool of strand-like material comprising a core with the strand-like material wound in crossed relationship thereon, the sides of said spool comprising discs of relatively soft plastic material extending from the core to the outermost windings of the strand on said spool, the outer surfaces of said discs having grooves extending over substantially the entire area thereof to weaken the structure of the discs causing said discs to break up into particles removable from the spool in the process of unwinding the strand therefrom, said grooves being arranged circumferentially.

3. A spool of strand-like material comprising a core with the strand-like material wound in crossed relationship thereon, the sides of said spool comprising discs of relatively soft plastic material extending from the core to the outermost windings of the strand on said spool, the outer surfaces of said discs having grooves extending over substantially the entire area thereof to weaken the structure of the discs causing said discs to break up into particles removable from the spool in the process of unwinding the strand therefrom, said grooves being arranged circumferentially, and including other grooves extending between and joining adjacent circumferential grooves.

4. A spool of strand-like material comprising a core with the strand-like material wound in crossed relationship thereon, the sides of said spool comprising discs of a wax base plastic material, the adherent properties of said material being such as to contact that portion of the windings of said strand abutting the discs to retain said windings against accidental unravelling, and the outer surfaces of said discs having a series of radially spaced circumferentially extending grooves weakening the structure of the discs to cause the same to break down into particles automatically removable from the spool in unwinding the strand therefrom.
- 10 5. A spool of strand-like material comprising a core with the strand-like material wound in crossed relationship thereon, the sides of said spool comprising discs of a wax base plastic material, the adherent properties of said material being such as to contact that portion of the windings of said strand abutting the discs to retain said windings against accidental unravelling, the outer surfaces of said discs having a series of radially spaced circumferentially extending 15 grooves weakening the structure of the discs to cause the same to break down into particles automatically removable from the spool in unwinding the strand therefrom, and said discs having other impressions on the outer surfaces thereof 20 joining at least part of the radially spaced grooves.
- 25 6. The herein described method of producing spools of the character described, which consists in first winding upon a suitable core a strand 25 of material in cross windings to form a circumferential strand body on said core, then applying a plastic composition to one side surface of said strand body, allowing the composition to congeal, then rotating said body with respect to a tool 30 exposed to the treated surface thereof to form circumferentially extending grooves in the composition and to remove surplus composition material to form on said surface a side disc or flange directly contacting the windings of the 35 strand on said spool disposed at said side of the strand body.
- 30 7. The herein described method of producing spools of the character described, which consists in first winding upon a suitable core a strand 40 of material in cross windings to form a circumferential strand body on said core, then applying a plastic composition to one side surface of said strand body, allowing the composition to congeal, then rotating said body with respect to a tool 45 exposed to the treated surface thereof to form circumferentially extending grooves in the composition and to remove surplus composition material to form on said surface a side disc or flange directly contacting the windings of the 50 strand on said spool disposed at said side of the strand body.
- 35 8. The herein described method of producing spools of the character described, which consists in first winding upon a suitable core a strand of material in cross-windings to form a circumferential strand body on said core, then applying a 55 plastic composition to one side surface of said strand body, allowing the composition to congeal, then rotating said body with respect to a tool exposed to the treated surface thereof to form circumferentially extending grooves in the composition and to remove surplus composition material to form on said surface a side disc or flange directly contacting the windings of the strand on said spool disposed at said side of the strand body, then similarly treating and processing the other side surface of said strand body, and then forming other impressions in the surfaces of the discs or flanges of said spool.
- 40 9. The herein described method of forming the side flanges or facings of spools, which consists in arranging a spool body consisting of a cross-wound strand upon a supporting spindle, then applying a heated wax-like composition to at least one surface of said strand body in a series of intermittent applications, then rotating the spindle at high speed to distribute the composition on said surface, and then forming circumferential grooves in said composition facing while the spool is rotated by said spindle.
- 45 10. The herein described method of forming the side flanges or facings of spools, which consists in arranging a spool body consisting of a cross-wound strand upon a supporting spindle, then applying a heated wax-like composition to at least one surface of said strand body in a series of intermittent applications, then rotating the spindle at high speed to distribute the composition on said surface, then forming circumferential grooves in said composition facing while the spool is rotated by said spindle, and trimming the facing to a predetermined thickness in said 50 grooving operation.
- 50 11. The herein described method of forming the side flanges or facings of spools, which consists in arranging a spool body consisting of a cross-wound strand upon a supporting spindle, then applying a heated wax-like composition to at least one surface of said strand body in a series of intermittent applications, then rotating the spindle at high speed to distribute the composition on said surface, then forming circumferential grooves in said composition facing while the spool is rotated by said spindle, trimming the facing to a predetermined thickness in said 55 grooving operation, and otherwise characterizing said facing.
- 55 12. The herein described method of forming the side flanges or facings of spools, which consists in arranging a spool body consisting of a cross-wound strand upon a supporting spindle, then applying a heated wax-like composition to at least one surface of said strand body in a series of intermittent applications, then rotating the spindle at high speed to distribute the composition on said surface, and then trimming and 60 characterizing the composition facing throughout the entire area thereof to form weakened wall structures whereby in the removal of the strand from the spool the composition facing will be intermittently removed in small particles.

DAVIS MARINSKY.
LOUIS H. MORIN.
